DISPLAY BOOKLET

André Vincent Vien, Villeneuve-le-Roi, France, assignor to L'Oréal, Paris, France

Filed Jan. 27, 1969, Ser. No. 15,515

Claims priority, application France Oct. 22, 1968

Term of patent 14 years

Int. Cl. D19—99

U.S. Cl. D97—2

FIG. 1 is a plan view of a display booklet oriented in an open condition; showing my new design;

FIG. 2 is a plan view as seen from the opposite side of FIG. 1;

FIG. 3 is a side elevation taken from the right of FIG. 1; and

FIG. 4 is an end elevation taken from the remote end of the hinge, the booklet being in a closed position.

The conventional indicia shown in broken lines is for illustrative purposes only and does not form part of the claim.

I claim:

The ornamental design for a display booklet, as shown and described.
